UNITED STATES PATENT OFFICE.

FRED W. COAN, OF MANCHESTER, NEW HAMPSHIRE.

MACHINE FOR OPENING AND FLATTENING SEAMS.

1,071,298.

Specification of Letters Patent.

Patented Aug. 26, 1913.

Application filed June 24, 1912. Serial No. 705,381.

To all whom it may concern:

Be it known that I, FRED W. COAN, a citizen of the United States, and resident of Manchester, in the county of Hillsboro 5 and State of New Hampshire, have invented new and useful Improvements in Machines for Opening and Flattening Seams, of which the following is a specification.

My invention relates to machines for 10 opening, smoothing and flattening seams in knitted, textile and other fabrics.

In the manufacture of many classes of 15 garments and the like, the sewing of the goods results in projecting seams which must of necessity be smoothed or flattened out before the garment is ready to wear. For example, in the manufacture of knit 20 underwear the sewing of the adjacent edges of the garment leaves a projecting ridge-like seam known as an "over edge" seam which must be flattened out in the process of manufacture. My invention is adapted and intended for this type of work generally, and it has proved in use peculiarly adapted 25 for the smoothing and flattening of the "over edge" seams of knit underwear.

Referring to the drawings which illustrate an embodiment of my invention,—Figure 1 is a side elevation partly in section of a seam flattening machine, embodying one form of my invention; Fig. 2 is a section on line 2—2 of Fig. 1; Fig. 3 is an enlarged sectional view on line 3—3 of Fig. 4; Fig. 4 is a front elevation of the machine shown in Fig. 1; Fig. 5 is a plan view of the parts shown in Fig. 3 with the plate J removed; Fig. 6 is a plan view of the striker; and Fig. 7 is a section on line A—A of Fig. 3.

40 A is the machine head or frame having a lower frame member A' and an upper frame member A². The driving shaft (not shown) is provided with a bevel gear B which meshes with a bevel gear B' fast on a counter shaft C journaled in said head A and offset at C' to form a crank. Within said head A and near the base thereof there is journaled a shaft D provided with a crank-arm d' connected by a pitman c with the 45 crank offset c'. Said shaft D is also provided with a crank-arm d² having a sliding bearing d³ for the crank-pin e' secured to the end of the crank E which is fast to the rock-shaft F. Said rock-shaft F, is pro-

vided with suitable bearings in the lower 55 frame member A' of the machine head A, and has a cam G fast on its outer end.

At the base of the machine head or frame A, upon two bearing points h, is a shaft H provided with a crank h' to which is secured 60 one end of a pitman c². The other end of said pitman c² is forked, the arms of the fork being formed as plates c³ which embrace a cam c⁴ fast to the countershaft C. Said shaft H is further provided with a 65 crank h² to which is secured a bar I, provided with suitable bearings and extending along the lower frame member A' above the rock-shaft F. The link N is pivoted at n' to the pitman c² and at n² to the machine 70 head or frame A.

Near the outer end of the lower frame member A' is secured an anvil plate J having parallel slots j and a plurality of projections j' spaced apart and located between 75 said slots j. Preferably the plate J projects beyond the end of the lower frame member A' and is provided with a seam guide j², for the purpose presently to be described.

Upon the lower frame member A' below the plate J is mounted a feed plate K which constitutes the feeder hereinafter referred to. The said feed plate or feeder is centrally slotted to permit the upper working 85 face thereof to be raised above the plane of the face of the plate J in the manner presently to be described and has a rearward extension k which is secured to the outer end of the bar I. A spring h' also secured to the 90 outer end of the bar I, bears against a portion of the lower frame member A' to press the bar I downward into contact with the cam G on the upper end of the rock-shaft F. The end of the bar I is squared, and the 95 web A³ near the outer end of the lower frame member A', is cut away to form a sliding bearing for the squared end of the bar I. The lower frame member A' is also cut away at its end to afford room for the 100 feed plate K in its lower position.

It will be clear that the movement of the countershaft C transmitted through the crank offset c', pitman c, crank-arms d', d², crank-pin e' and crank E, gives to the rock-shaft F, and the cam G secured thereto, a 105 rocking motion; and that the movement of the countershaft C transmitted through the

pitman c^2 , link N, crank h' , shaft H, and crank h^2 , gives to the bar I a longitudinal reciprocating motion, so that the feed plate K being fast to the rod I, and the rod I being in contact with the cam G, the feed plate is given an up-and-down and back-and-forth motion, that is, a characteristic four motion feed movement.

Upon the upper frame member A^2 and above the plate I, is a striker consisting of a rod L mounted in suitable guide-blocks l and having a head L' provided with a plurality of cross-bars l² adapted to pass between the projections j' of the plate J when the head L' is brought against the plate J, as presently to be described. It will be apparent that the cross-bars l² are in effect dentations adapted to register with the openings between the projections j' on the plate J. Therefore, if desired, the head L' may be made solid and provided with projections or dentations adapted to register with said openings between the projections j'. Preferably, the inner end or tail W of the head L' is wedge-shape, as shown in dotted lines at W in Fig. 6, to aid in the flattening out of the seam after it has been fed over and passed beyond the projections j'.

A spring M surrounding the rod L and held between one of said guide-blocks l and a block l³ on said rod, serves normally to hold said head L' against said anvil plate J. For convenience in inserting and removing the work, the said block l³ is preferably provided with a lug l⁴, and a cam l⁵ adapted to coöperate therewith is pivoted to the machine head or frame A, whereby the head L' may be lifted and held out of contact with the plate J.

The operation of the machine is as follows: The operator raises the striker by means of the cam l⁵, and places the material Z upon the anvil plate J, the seam being laid across the projections j' and the seam guide j². The striker is then brought down upon the material, the cross-bars l² on the head L' forcing the seam downwardly between the projections j', as clearly shown in Fig. 3. When now the power is applied, the parts being in the position shown in Fig. 3, the feed plate K by reason of the actuating means already described performs its characteristic four-feed motion. First, it rises through the parallel slots j of the anvil plate J, and, overcoming the force of the spring M, forces the head L' and the material out of contact with the anvil plate. It then moves toward the left, as viewed in the drawings (Figs. 1 and 3), retaining the material and head L' out of contact with the anvil plate and feeding the material forward. It then drops below the plane of the face of the anvil plate, thus permitting the force of the spring M to return the head L' into contact with the anvil plate with the

material held therebetween. It then moves to the right, as viewed in the drawings, to the position from which it started.

It will be clear that when the feed plate at the end of its movement to the left drops suddenly below the plane of the face of the anvil plate, the force of the spring M will cause the head L' to strike upon the anvil plate with a sharp percussive blow, the cross-bars or dentations l² forcing the seam down between the projections j'. It will be apparent that when the seam is thus forced down between the projections j', it is not only pounded but also stretched longitudinally, and as the action of the machine is very rapid the seam is subjected many times to this stretching and pounding before it is fed out from between the striker and anvil plate. As a result of this longitudinal stretching and pounding, the seam is stretched, opened and flattened. It is then fed under the wedge-shaped tail piece W of the head L' and subjected to lateral stretching and further pounding, so that when the seam is finally fed out from beneath the striker it has been thoroughly stretched, opened and flattened.

What I claim and desire to secure by Letters Patent is:

1. A machine of the class described, comprising a feeder adapted to feed material, means for longitudinally stretching and flattening a portion of a seam in said material, and means for subsequently laterally stretching said portion of the seam. 95

2. A machine of the class described, comprising a striking member and an anvil member, one of said members having a plurality of projections spaced apart, and the other of said members having a dentation adapted to register with the opening between said projections, and means to actuate said striking member. 100

3. A machine of the class described, comprising a striking member and an anvil member, one of said members having a projection and the other of said members having an opening to permit said projection to pass therein, and means to actuate said striking member. 110

4. A machine of the class described, comprising a striking member, an anvil member, and a feeder, one of said members having a projection and the other of said members having an opening to permit said projection to pass therein, and means to actuate said striking member. 115

5. A machine of the class described, comprising an anvil plate having a projection, and a striker having an opening adapted to permit said projection to pass therein, and means to actuate said striker. 125

6. A machine of the class described, comprising an anvil plate having a projection, and a striker having an opening adapted to 130

- permit said projection to pass therein, a feeder, and means to actuate said striker.
7. A machine of the class described, comprising an anvil plate having a plurality of 5 projections spaced apart, a striker having a plurality of cross-bars adapted to pass between said projections, and means to actuate said striker.
8. A machine of the class described, comprising a plate having a projection, a spring-pressed striker located above said plate and having an opening to permit said projections to pass therein, a feeder adapted to feed material and intermittently to raise 15 said striker, and means to actuate said feeder.
9. A machine of the class described, comprising a plate having a plurality of projections spaced apart, a spring-pressed striker located above said plate and having a plurality of cross-bars adapted to pass between said projections, a feeder adapted to feed material and intermittently to raise said striker, and means to actuate said feeder.
10. A machine of the class described, comprising a plate having a plurality of projections spaced apart, a spring-pressed striker located above said plate and having a dentation adapted to register with the opening between said projections, a feeder adapted to feed material and intermittently to raise said striker, and means to actuate said feeder.
11. A machine of the class described, comprising a striker, an anvil plate, and means 35 normally to hold said striker against said anvil plate, a feeder adapted to feed material and intermittently to force said striker out of contact with said anvil plate, and means to actuate said feeder.
12. A machine of the class described, comprising an anvil plate having a projection, a striker having an opening adapted to permit said projection to pass therein, means normally to hold said striker against said 45 anvil plate, a feeder adapted to feed material and intermittently to force said striker out of contact with said anvil plate, and means to actuate said feeder.
13. A machine of the class described, comprising an anvil plate having a plurality of 50 projections spaced apart, a striker having a plurality of cross-bars adapted to pass between said projections, means normally to hold said striker against said anvil plate, a feeder adapted to feed material and intermittently to force said striker out of contact with said anvil plate, and means to actuate said feeder.
14. A machine of the class described, comprising an anvil plate having a plurality of 55 projections spaced apart, a striker having a head provided with a plurality of cross-bars adapted to pass between said projections, a
- spring adapted normally to hold said head against said anvil plate, a feeder adapted to 65 feed material and intermittently to force said head out of contact with said anvil plate, and means to actuate said feeder.
15. A machine of the class described, comprising an anvil plate having a plurality of 70 longitudinal slots and a plurality of projections located therebetween and spaced apart, a striker having a head provided with a plurality of cross-bars adapted to pass between said projections, means normally to hold 75 said head against said plate, a feeder located under said anvil plate and having a central longitudinal slot, means intermittently to raise said feeder to force said head out of contact with said anvil plate and thereafter 80 to lower said feeder to permit said head to return to normal position against said anvil plate, and said feeder adapted to feed material.
16. A machine of the class described, comprising a striker, an anvil plate, and means 85 normally to hold said striker against said anvil plate, a feeder adapted to feed the material and intermittently to force said striker out of contact with said anvil plate, and means to actuate said feeder comprising a rock-shaft provided with a cam, and a reciprocating rod yieldingly held against said cam.
17. A machine of the class described, comprising an anvil plate having a plurality of 95 longitudinal slots and a plurality of projections located therebetween and spaced apart, a striker having a head provided with a plurality of cross-bars adapted to pass between 100 said projections, means normally to hold said head against said plate, a feeder located under said anvil plate and having a central longitudinal slot, means comprising a rock-shaft provided with a cam, and a reciprocating rod yieldingly held against said 105 cam intermittently to cause said feeder to force said head out of contact with said anvil plate, and thereafter to lower said feeder to permit said head to return to normal position against said anvil plate, and said feeder adapted to feed the material.
18. A machine of the class described, comprising an anvil plate having a plurality of 110 projections, and a striker having a head provided with a wedge-shaped tail, and a dentation adapted to register with the opening between said projections, a feeder adapted to feed material and to actuate said 115 striker to flatten a seam in the material.

Signed by me at Manchester, New Hampshire, this 15th day of June 1912.

FRED W. COAN.
